HIS ATTORNEY.

UNITED STATES PATENT OFFICE.

PAUL CALDWELL, OF PITTSBURGH, PENNSYLVANIA, ASSIGNOR TO GENERAL ELECTRIC COMPANY, A CORPORATION OF NEW YORK.

MOTOR-STARTING DEVICE.

1,098,780.

Specification of Letters Patent. Patented June 2, 1914.

Application filed April 5, 1913. Serial No. 789,120.

To all whom it may concern:

Be it known that I, PAUL CALDWELL, a citizen of the United States, residing at Pittsburgh, county of Allegheny, State of Pennsylvania, have invented certain new and useful Improvements in Motor-Starting Devices, of which the following is a specification.

My invention relates to the control of electric motors and has for its object the provision of means whereby an electric motor may be started and stopped in a simple and reliable manner under conditions which reduce to a minimum all possibility of damage from abnormal circuit conditions and improper handling.

In the control of electric motors, especially induction motors, it is desirable that the operation performed by the operator of starting and stopping the motor be simplified and rendered proof against improper handling as far as possible. These operations are usually performed by employees having practically no knowledge of electrical apparatus. It is desirable that the operation be limited to the throwing of the switch and that the arrangement be such that the operation cannot be improperly performed so as to injure the apparatus by dangerous arcing. Such motor starting apparatus is ordinarily provided with overload protection whereby the motor circuit will be automatically opened upon the occurrence of an overload on the circuit. Upon the occurrence of such an overload it is desirable that the motor circuit cannot be again started until the operator performs some operation with the control apparatus, such, for instance, as the throwing of the switch. This insures that the apparatus will not be restarted without the knowledge of the operator.

In carrying out my invention I provide means whereby the starting operation may be performed by the throwing of a manually operated line switch, the arrangement being such that the motor circuit will always be opened by an electro-magnetic circuit breaker whether it is opened intentionally or by an overload. In order to again close the motor circuit after it has been opened by an overload it is necessary for the operator to open and close the line switch. It is frequently desirable that in addition to the

manually operated line switch one or more control switches located at a remote point from the line switch be provided. When such a control switch is used in my starting apparatus, the motor circuit will be opened and closed at the circuit breaker by the operation of the control switch assuming that the line switch is closed. Upon the occurrence of an overload, however, the circuit breaker will open and cannot be closed by the operation of the control switch but can only be closed by first opening and closing the line switch and then operating the control switches.

In one embodiment of my invention I place the line switch and other control apparatus in a casing preferably of metal and have nothing projecting from the casing but the handle of the line switch. This casing is preferably completely closed so that the operator will not ordinarily have access thereto. In case the control switch is employed it is located externally of the casing and preferably remote therefrom so that in case the motor should be stopped by the occurrence of an overload the operator must go back to the starting apparatus and operate the line switch by the handle projecting through the casing and then return and operate the control switch to start the motor.

Other objects and purposes of my invention will appear in the course of the following specification, in which I have shown my invention embodied in concrete form for purposes of illustration.

In the drawing, Figure 1 is a diagram of the circuit connections and Fig. 2 represents the parts inclosed in a casing or box.

Referring first to Fig. 1, A represents the armature, F the series field and F' the shunt field of the motor to be controlled. I have shown a compound wound motor for purposes of illustration, but it is obvious that my invention is in no sense limited to this particular type of motor. S represents a main or line switch for connecting the motor to the line. This switch has, in addition to the main contacts 10 and 11, the auxiliary contacts 12 and 13 for purposes hereinafter described. The arrangement is such that as the switch closes contact 13 is first engaged and then the contact 11. When the switch is fully closed the contacts 10, 11 and 12

are in engagement with the switch arms, but contact 13 is out of engagement. The particular construction of this switch forms no part of my invention, but is merely illustrated in a conventional manner. One of the switch arms 14 is longer than the other so as to engage the contact 13 during the closing of the switch and to engage the contact 12 after the switch is closed. An electromagnetic switch or conductor B having a winding 15 and a switch arm 16 is provided for opening and closing the motor circuit after the line switch is closed. Associated with this contactor is an overload relay for interrupting the circuit of the contactor upon the occurrence of overload conditions. This relay forms no part of my invention, but is described and claimed in an application of Edwin J. Murphy, Serial No. 674,979, assigned to the same assignee as this application. Briefly described, this relay consists of two pivoted switch arms 17 and 18. The switch arm 17 is moved to closed position upon the energization of winding 19 and when in its closed position the winding 15 of the contactor is energized. The switch arm 18 controls the circuit of the actuating winding 19 and is moved to closed position in which the winding 19 is energized by the core of the overload coil 20. The two switch arms 17 and 18 are mechanically interlocked so that each holds the other in closed position. The interlock consists of a tail piece 21 on the switch arm 18 having two notches 22 and 23 for engaging the lug 24 on the end of the switch arm 17. When the switch arm 17 is in closed position, it is held closed by the engagement of the lug 24 in the notch 22. Upon the occurrence of an overload the coil 20 will lift its core, release the switch arm 17, which will be moved to open position by the weight of the core, and move the switch arm 18 to closed position. In this position of the switch arm 18 the coil 19 may be energized to again close or reset the switch arm 17 to energize the coil 15 of the contactor B. A control switch 25 having one terminal connected with the contact 12 and the other with the winding 15, is provided for opening and closing the circuit of the contactor through the switch arm 17 of the relay. This switch 25 is not essential to my invention and in case it is not used the contactor B will close as soon as the line switch is closed and will open before the line switch is fully opened. The actuating coil 19 of the relay has one terminal connected with the contact 13, while the other terminal is connected with the switch arm 18. R and R' represent two resistance sections which are successively cut out of the motor circuit to bring it up to running speed. These resistances are cut out of circuit by means of two electromagnetic switches C and C'. These

two switches are of the type described and claimed in the application of Edwin J. Murphy, Serial No. 608,652. The arrangement is such that when the current through the actuating winding of a switch is relatively high, the switch will not close but when the current falls to a predetermined value it will close and cut out a section of resistance. The switch C is provided with an additional winding 26 connected across the line for holding the switch closed when the current becomes very low due to a very light load on the motor. This coil is connected in circuit by a small auxiliary switch shown conventionally as consisting of a pivoted arm 27 engaging the contact 28 when the switch C closes.

The mode of operation and the circuit connections of the apparatus are as follows: Assuming the parts to be in the position shown in the drawing and it is desired to start the motor, the operator first closes the line switch S. During the closing of this switch the long arm of the switch first engages the contact 13. In this position the actuating winding 19 of the overload relay will be energized, the circuit being from the positive side of the line to the contact 13, winding 19, switch arm 18 and wire 29 to the negative side of the line. This brings the contact arm 17 to closed position and opens the circuit of the winding 19 at the contact arm 18. This happens during the movement of the line switch S to closed position. When the switch is in closed position the operator may then operate the control switch 25 which may be located at some remote point. On the closing of the switch 25 the contactor B will close, the circuit being as follows: From the positive side of the line to contact 12, switch 25, winding 15, wire 30, switch arm 17, wire 29 and back to the negative side of the line. The contactor B being closed, the motor circuit will be established from the positive side of the line through the field F, armature A, resistance R', winding of contactor C', resistance R, through the overload coil 20, contact arm 16, to the negative side of the line. As the motor speeds up and the current reduces to a suitable value, the contactor C' will close, short circuiting the section of resistance R' through the winding of the contactors C. Finally after the current reaches the proper value the contact of the contactor C will close thereby short circuiting the resistance R and the winding of contactor C'. The contactor C' will then open and the motor will be connected across the line. Upon the closing of the contactor C the winding 26 is connected in circuit through contacts 27 and 28, the circuit being from the positive side of the line through the contact 12, control switch 25, contacts 28 and 27, winding 26, wire 30, contact arm 17 of the overload

relay to the negative side of the line. The energizing of the coil 26 holds the switch 17 in closed position since the actuating coil has been cut out of circuit. The motor 5 is now running at full speed under normal conditions. By opening and closing the switch 25 the motor may be started and stopped automatically at any time as desired, so long as normal conditions exist. 10 If, however, an overload should occur, control at the switch 25 is lost since the switch arm 17 of the overload relay opens and opens the circuit of the winding 15 of the contactor independently of the control switch. When the switch arm 17 opens, the switch arm 18 closes and is held closed by the interlocking connection between the switch arms. In order to again start the motor it is necessary for the operator to 20 open and close the switch S. In opening the switch the contact 13 is engaged by the long arm 14 of the switch and energizes the winding 19 which closes the relay. With the switch S in the closed position the control switch 25 may again be operated as before to close the contactor and start the motor.

In Fig. 2 I have shown a casing or box mounted upon a standard for containing 30 the control apparatus above described. This box is preferably made of metal and is preferably locked so as to prevent access thereto except to the proper persons. A lever 31 is mounted upon a shaft extending through 35 the casing. By moving the lever from the position shown in the drawing to the position shown in dotted lines the switch will be opened, and the switch will be closed when the lever is in the position shown in 40 the full lines. I may also and preferably do provide means for locking the switch lever in the open position as shown in the drawing. With this arrangement no part of the control apparatus is exposed with the 45 exception of the lever and it is only necessary upon the occurrence of an overload for the operator to move the lever 31 down to open position shown in dotted lines and back again to restore control to the control 50 switch 25. This insures that the operator will return to the motor and control apparatus after an overload has occurred to see that everything is all right before restarting. It also insures that the motor will 55 not be started without the knowledge and consent of the operator.

While I have described my invention as embodied in concrete form and as operating in a specific manner for purposes of 3 illustration in accordance with the provisions of the patent statutes, it should be understood that I do not limit my invention thereto, since various modifications thereof will suggest themselves to those skilled in 5 the art without departing from the spirit of

my invention, the scope of which is set forth in the annexed claims.

What I claim as new and desire to secure by Letters Patent of the United States, is:

1. The combination with an electric motor, 70 of a manually operated line switch for controlling the circuit thereof, electromagnetic means for opening the motor circuit independently of said line switch upon the occurrence of overload conditions, connections 75 whereby the motor circuit cannot be again closed after it has been opened on an overload until the line switch is operated, and a control switch for opening and closing the motor circuit under normal circuit conditions with the line switch closed. 80

2. The combination with an electric motor, 85 of a manually operated line switch for controlling the circuit thereof, an electromagnetic switch having its contacts in series with the contacts of the line switch for closing the motor circuit, means whereby said electromagnetic switch is opened upon the occurrence of overload conditions, connections 90 whereby said electromagnetic switch cannot be closed after it has been opened by an overload until the line switch is operated, and a control switch arranged to control the circuit of the electromagnetic switch under normal conditions with the line switch 95 closed.

3. The combination with an electric motor, 100 of a manually operated line switch for controlling the circuit thereof, an electromagnetic switch having its contacts in series with the contacts of the line switch for closing the motor circuit, an overload relay controlling the circuit of the electromagnetic switch, connections 105 whereby said relay is electromagnetically closed during the operation of the line switch, and a control switch for energizing the electromagnetic switch through the closed contacts of the relay to close the motor circuit.

4. The combination with an electric motor, 110 of a manually operated line switch for controlling the circuit thereof, an electromagnetic switch having its contacts in series with the contacts of the line switch for closing the motor circuit, an electromagnetically 115 closed overload relay controlling the circuit of the electromagnetic switch, a contact on the line switch for closing the actuating circuit of the overload relay during the operation of the manual switch, and a control switch for energizing the electromagnetic switch through the closed contacts of the relay to close the motor circuit. 120

5. The combination with an electric motor, 125 of a manually operated line switch for controlling the circuit thereof, an electromagnetic switch having its contacts in series with the contacts of the line switch for closing the motor circuit, an electromagnetically closed overload relay controlling the 130

circuit of the electromagnetic switch, a control switch for the electromagnetic switch, and auxiliary contacts on the line switch for closing the actuating circuit of the relay
5 during the operation of the switch and connecting the control switch to line when the line switch is closed.

In witness whereof, I have hereunto set my hand this twenty-ninth day of March, 1913.

PAUL CALDWELL.
